(57) **CLAIM**

The ornamental design for a container for rolling tobacco and cannabis, as shown and described.

DESCRIPTION

FIG. 1 is a top view of a container for rolling tobacco and cannabis;

FIG. 2 is a bottom view thereof;

FIG. 3 is a right side view thereof;

FIG. 4 is a left side view thereof;

FIG. 5 is a front view thereof;

FIG. 6 is a rear view thereof;

FIG. 7 is a front right side perspective view thereof in closed condition;

FIG. 8 is a front right side perspective view thereof in open condition;

FIG. 9 is a front right side perspective view thereof in open condition showing unclaimed tools in broken lines;

FIG. 10 is a front left side perspective view thereof in closed condition;

FIG. 11 is a front left side perspective view thereof in open condition; and,

FIG. 12 is a front left side perspective view thereof in open condition showing unclaimed tools in broken lines.

The broken lines in the drawings depict portions of the container for rolling tobacco and cannabis that form no part of the claimed design.
